LUBRICATOR

Filed Oct. 7, 1924

Inventor
James J. Hennessy
By Cornwall, Bedell & Janus, ATTYS.

UNITED STATES PATENT OFFICE.

JAMES J. HENNESSY, OF NEW YORK, N. Y.

LUBRICATOR.

Application filed October 7, 1924. Serial No. 742,253.

My invention relates to journal lubricators such as are used on railway rolling stock and consists in an improved apparatus for supplying lubricant to the surface of an axle 5 journal.

My lubricator is of the type in which a pump is utilized to raise the lubricant from a reservoir or cellar to a waste container or other device for distributing lubricant over 10 the journal, and one of the objects of my invention is to limit the amount of lubricant fed to the distributor by the pump, irrespective of certain variations in the operation of the pump plunger.

Another object of my invention is to adapt 15 a pump of the type utilized so that the same will operate in a particular type of reservoir when the lubricant level in the reservoir is below the body of the pump.

Another object of my invention is to provide 20 a pumping and distributing device so mounted in the reservoir that it may follow any movement of the journal relatively to the reservoir.

Another object of my invention is to remove 25 surplus lubricant from the journal surface as it leaves the lubricant distributing member. All of these particular objects combine to provide a more efficient lubrica-

tor in which the lubricant is supplied to the 30 journal more evenly than heretofore and waste of the lubricant is avoided.

In the accompanying drawings which illustrate 35 my invention—

Figure 1 is a vertical longitudinal section 40 through my improved lubricator and shows the same applied to the journal of a car axle.

Figure 2 is a transverse vertical section 45 on line 2—2 of Figure 1.

Figure 3 is a detail view taken substantially 50 on line 3—3 of Figure 1.

Figure 4 is a top view of a journal wiper detail described hereafter.

The car axle journal and wheel hub are 55 shown at A and B, respectively, and it will be understood that the axle carries a suitable journal or driving box (not shown) through which the load is transferred to the axle. The lubricator positioned in such 60 box comprises a cellar or reservoir 1, a pump 2, and a sub-cell or distributor 3. The body of pump 2 is provided with a downwardly extending lug 4 located approximately 65 below the center of the distributor and forming a bearing on which the pump

may pivot freely to a limited extent. The distributor 3 is yieldingly supported on pump 2 by means of a spring 5. Preferably, the distributor is filled with waste or other suitable packing material by means of which 60 lubricant supplied to the center of the distributor by the pump may be spread by capillary attraction throughout the area of the distributor.

The pump body includes a horizontal inlet passage and a vertical discharge passage equipped with check valves 6 and 7, respectively. The pump piston 8 is normally thrust to the left by a coil spring 9 and is positively moved to the right by an actuating element 10 which projects through the side wall of the cellar and is adapted to be engaged by the inner face of the wheel hub B on journal A.

It is obvious that shifting of the journal 75 and wheel longitudinally of their axis and through the journal or driving box will serve to operate the pump to force lubricant from the reservoir to the upper end of the discharge passage. This broad arrangement 80 forms no part of my present invention as the same is described in copending applications filed by me, for instance, Serial No. 578,018, filed July 27, 1922.

Due to the viscosity of heavy oils, especially 85 in cold weather, the diameter of the pump piston cannot be safely reduced below a certain minimum, approximately three-eights of an inch, and with a piston of this diameter longitudinal movement exceeding 90 one-half inch is objectionable for the reason that a greater amount of oil is pumped than can be distributed without flooding the distributor and being wasted by being thrown out of the box by the journal.

To limit the travel of the pump piston, I provide a stop for element 10 which, however, may be automatically adjusted to provide the desired reciprocal movement of the element and the pump piston. This stop is 100 here illustrated as a ring 11 of spring material compressed within the bearing for element 10 and surrounding the reduced portion 12 of the element. Movement of the wheel hub B to the right will positively 105 force ring 11 inwardly of its bearing. Subsequent movement of element 10 to the left will be limited by the engagement of its righthand shoulder with ring 11, although shifting of the journal in the box may per- 110

mit hub B to move a substantially greater distance away from the end of element 10. If the movement of hub B to the right, which positions ring 11, was an abnormal movement, which is not duplicated for a lengthy period, the jarring of the apparatus over the rail and the repeated tapping of the element shoulder against the inner face of ring 11, will gradually move the latter to the left until ring 11 is as far out as the normal inward movement of the hub will permit. By means of this device, the stroke of the pump piston may be maintained fairly constant and the length of this stroke is controlled by the length of the reduced portion 12 of the piston 10.

Resting on check valve 7 and slidably in the pump discharge passage is a plunger 13 provided with a restricted aperture 14 of substantially smaller cross sectional area than the interior of the pump cylinder and piston. When the pump piston moves inwardly on its discharge stroke, the lubricant forced through the discharge passage (in excess of the amount which can pass through aperture 14) will lift plunger 13 until the lower end of the latter uncovers a by-pass 15 in the wall of the discharge passage which permits excess lubricant to return to the reservoir. By means of this arrangement lubricant will be discharged through aperture 14 in a succession of short squirts. Usually a substantially larger amount of lubricant will be returned to the reservoir through the by-pass, thus avoiding excessive supply to the journal.

A spring supported delivery sleeve 16 surrounds the pump discharge passage and forms a restricted passage insuring free flow of lubricant to the surface of the journal. A. A pin 17 traverses the pump discharge passage and projects into a longitudinal slot 18 in sleeve 16. This pin limits the upward movement of the sleeve and also limits the upward movement of plunger 13, thus preventing the disassembly of these elements with the pump body when the lubricator is removed from the box.

To prevent the surface of the journal carrying a surplus amount of lubricant upwardly and throwing it out of the box by centrifugal force, I prefer to provide wiping elements at the edges of the distributor and these elements may be provided by extending the sides of the distributor as shown at 19 in Figure 2, and also by providing separate wiping elements, such as strips 20, mounted on suitable springs 21 which rest on the floor of the distributor. With the latter structure, I can use strips of fiber or other relatively soft material which will be worn into a contour which follows the journal. In my preferred construction, I show upstanding flanges 22 on the floor of the sub-cell and I slot springs 21 so that

they fit over these lugs and may be held in position by suitable cotters 23.

Another feature of my invention is the provision of the pump intake 24 in the form shown in Figure 1 and Figure 3 in which the intake opens downwardly and is enlarged as shown to afford free passage to the pump cylinder. The opening in the intake is provided with a screen 25 and the enlarged opening permits a substantial portion of the screen to be choked without interfering with the operation of the pump. The downwardly directed terminal of the intake permits the pump to function at a lower level of lubricant in the reservoir than possible with the horizontal terminal of the pump body previously provided. In order to permit access to the inlet valve and interior of the pump cylinder, I provide a removable plug 26 in the wall of intake 24 and aligned with the pump cylinder.

My invention eliminates the necessity of manual adjustment of each lubricator, upon installation of the same, in order to secure the best results in the operation of the lubricator. It also eliminates the supply of an excess quantity of lubricant to the journal irrespective of care utilized in the original installation or of wear of the journal box liners during the life of the rolling stock.

Obviously, details in the construction of my invention may be made without departing from the spirit thereof and I contemplate the exclusive use of such modifications as are included in the appended claims.

I claim:

1. In a journal lubricator, a pump including a pump actuating element operated by relative movement between the lubricator and a surface on the journal to be lubricated and movable throughout the extent of said relative movement, and means yieldingly limiting the extent of movement of said element to less than the total extent of said relative movement.
2. In a journal lubricator, a pump, a reciprocating pump actuating element adapted to be operated by movement relatively to the lubricator and a surface on the journal to be lubricated, an adjustable member for limiting the stroke of said element and adapted to be automatically adjusted by movement of said surface.
3. In a lubricator, a pump, a reciprocating pump actuating element, a bearing for said element, and means held frictionally in said bearing for normally limiting the reciprocal movement of said element.
4. In a lubricator, a pump, a reciprocating pump actuating element, a bearing for said element, and an expansible ring surrounding said element and frictionally engaging said bearing and adapted to engage said element to limit its reciprocal movement.
5. In a lubricator, a pump, a reciprocating

- ing pump actuating rod, a bearing for said rod, said rod being reduced in diameter throughout a portion of its length intermediate the ends of said bearing, and an expandable ring surrounding the reduced portion of said rod and seated in said bearing and adapted to engage the shouldered end of said reduced portion to limit movement of said rod.
6. In a journal lubricator, a pump including an inlet passage and a discharge passage, an apertured plunger in said discharge passage, and a by-pass in the wall of said discharge passage above the bottom of said plunger.
7. In a journal lubricator, a pump including an inlet passage and a discharge passage, a check valve at the beginning of said discharge passage, a by-pass in said discharge passage spaced from said valve, and an apertured plunger slidable in said discharge passage with one end extending between said by-pass and check valve.
8. In a journal lubricator, a pump including an inlet passage and a discharge passage, a check valve at the beginning of said discharge passage, an apertured plunger resting on said check valve and slidable in said discharge passage, and a by-pass in said discharge passage gradually uncovered by upward movement of said plunger during the pump discharge.
9. In a lubricator, a pump including an inlet passage, a discharge passage, a cylinder and piston all of substantial cross sectional area, a plunger in said discharge passage provided with an aperture of relatively small cross sectional area, and a by-pass of substantial size in said discharge passage and uncovered by said plunger during said pump discharge.
10. In a journal lubricator, a pump including a vertical discharge passage, a delivery sleeve surrounding said passage and slidable thereon, a plunger within said passage, a by-pass in said passage adapted to be opened by said plunger, and means for preventing movement of said sleeve over said by-pass and movement of said plunger out of said passage.
11. In a journal lubricator, a pump including a vertical discharge passage, a delivery sleeve surrounding said passage and slidable thereon, a plunger within said passage, a by-pass in said passage adapted to be opened by said plunger, a spring thrusting said sleeve upwardly, and a pin traversing said passage and preventing disassembly of said plunger and sleeve therewith.
12. In a journal lubricator, a lubricant reservoir, a horizontal pump cylinder above the bottom of said reservoir, a downwardly opening intake terminating below the lower portion of the interior of said cylinder, and a removable plug in the wall of said intake and aligned with said cylinder.
13. In a journal lubricator, a lubricant cellar, and a pumping device pivotally supported near its center on the floor of said cellar and including a lubricant discharge member located substantially over its point of support.
14. In a journal lubricator, a lubricant cellar, and a pumping device including a lubricant discharge member adapted to extend along a journal to be lubricated, said device having a downwardly projecting lug by which the device is supported upon the floor of said cellar so as to tilt freely with said journal relatively to said cellar.
15. In a journal lubricator, a lubricant reservoir or cellar and a sub-cellар containing means for distributing the lubricant to the journal to be lubricated, and a non-absorbent scraper movably mounted on said sub-cellар and yieldingly held against the journal surface near the side of said sub-cellар to remove surplus lubricant from the latter as it leaves the sub-cellар.
16. In a journal lubricator, a lubricant reservoir or cellar, a sub-cellар adapted to distribute lubricant to the journal to be lubricated, a yielding member mounted on the floor of said sub-cellар, and a strip of non-absorbent material held edgewise against said journal near the side of said sub-cellар by said member and formed of relatively soft material.
17. In a journal lubricator, a lubricant reservoir or cellar, a sub-cellар adapted to distribute lubricant to the journal to be lubricated, an upstanding perforated lug on the floor of said sub-cellар, a curved member of spring material slotted between its ends to fit over said lug and having an end extending upwardly toward said journal, a pin extending through said lug to hold said member in position, and a journal wiping element on the upwardly extending end of said member.
18. In a journal lubricator, a lubricant cellar and a pumping device having a rigid pivotal support and having a telescoping lubricant discharge passage over its point of support.
19. In a journal lubricator, a lubricant reservoir, a pump including a discharge passage leading from the pump cylinder to the journal to be lubricated and also including a normally closed discharge passage leading from the pump cylinder to said reservoir, and means for limiting the amount of lubricant discharged through said first-mentioned passage by the opening of said second-mentioned passage.

In testimony whereof I hereunto affix my signature this 17th day of September, 1924.

JAMES J. HENNESSY.
